WRINGER AND THE LIKE

Walter L. Kauffman, II, Erie, Pa., assignor to
Lovell Manufacturing Company, Erie, Pa., a
corporation of Pennsylvania

Application October 7, 1938, Serial No. 233,833

9 Claims. (Cl. 68—269)

Power wringers and similar devices involve a certain amount of hazard to persons operating them in that there is danger of the operator getting caught in the rolls. In order to reduce the hazard, devices have been provided for relieving the condition. The two methods generally employed are to release the pressure on the rolls, or to stop the driving action on the rolls, or both. In the present invention both methods may be employed. It will also be understood that when an operator is caught in the rolls, any action is under panic conditions, and must be accomplished very quickly. To this end some release devices are what might be termed instinctive release devices, that is to say, they respond to the instinctive pull or action of the operator caught. The present invention is designed to carry out an instinctive release.

Features and details of the invention will appear from the specification and claims. The invention is illustrated as a wringer in the accompanying drawing, as follows:

Fig. 1 shows a front elevation of the wringer partly in section.

Fig. 2 a section on the line 2—2 in Fig. 1.

Fig. 3 a section on the line 3—3 in Fig. 1.

Fig. 4 a section on the line 5—5 in Fig. 1, the parts being in neutral position.

Fig. 5 a section on the line 5—5 in Fig. 1.

Fig. 6 a section on the line 6—6 in Fig. 4.

Fig. 7 a perspective view of a frame supporting post.

Fig. 8 a perspective view of a frame carrying rocker.

1 marks the base of the wringer frame; 2 the stile opposite the driving end of the wringer; 3 the stile adjacent to the driving end; 4 the lower wringer roll; 4a the upper wringer roll; 5 and 6 the shafts for the lower and upper rolls respectively; 7 bearings for the shaft 5; 8 brackets supporting the bearings; 9 bearings for the upper shaft 6, the bearings 9 being slidingly mounted in the stiles; 10 a pressure spring operating on the upper bearings; 11 a headed adjusting screw operating through a nut 12, the nut being secured in the top bar 13. The top bar is detachable, being held to the stile 3 by detachable interlocking shoulders 14.

At the opposite end of the wringer a resetting lever 15 is hinged at 15a on the top bar. It is connected with the stile 2 by links 15b, the lever 15 and links 15b forming a toggle adapted to reset the pressure on the spring. The pivots of the links 15b and hinge 15a are so aligned as to retain the toggle in set position when the lever 55

is in its lowermost position. The lever 15 has an arm 15c which is engaged by an arm 16 pivotally mounted on the top and provided with a trip bar 16a. With the downward movement of the trip bar, the toggle lever is forced outwardly to unstable position, and the further movement of the toggle releases the pressure on the spring and thus the pressure on the rolls. This pressure release mechanism is more fully described in my Patent No. 2,233,385, dated Feb. 25, 1941.

Preferably springs 9a between the bearings 7 and 9 are provided for lifting the upper roll when the pressure is released, and springs 7a are provided under the lower bearings for lifting the shaft 5, and consequently its gear out of mesh as hereinafter described. A supporting head 17 is swiveled on a post 18, the post having a flange 19 with a number of perforations through it at its upper end adapted to receive a bolt 20 slidingly secured on the head. It is provided with a handle 21. A spring 22 yieldingly holds the bolt in locked position. This swivel connection permits the swinging of the head and the wringer, and the bolt locks them in adjusted positions. A drive shaft 23 is journaled in the post and is provided with a beveled driving gear 24 at its upper end. A beveled gear 25 meshes with the gear 24 and is carried by a shaft 26, journaled on a bearing 27 formed in a web 27a in the head. A gear 28 meshes with a gear 29 carried by a stud 30 extending from the web 27a. The gear 28 is fixed on the inner end of the shaft 26. The gear 29 meshes with a gear 31 journaled on a stud 32, the stud 32 being carried by a post extending from the web 27a. A gear 33 is fixed on the shaft 5 and communicates the driving movement to the roll.

The head is provided with a supporting arm 34 which extends laterally under the wringer frame. It is provided with the supporting posts 34a. Rockers 35 are pivotally mounted by means of studs 36 on the posts 34a. The rockers are pivotally connected with the bottoms of the stiles by studs 37 which extend through perforations in the outer walls of the stiles. The frame is connected with the web 27b of the head by means of a screw 39 which extends from the stile through a slot 40 in the web 27b, thus this connection permits of a pivotal movement of the wringer frame and also a vertical movement. The wringer is moved to set position by moving the bottom of the wringer on the rockers toward the rear. This drops the driven gear 33 into mesh with the reversing gear 31 and gives the rolls the forward rotative movement. Should the

operator become caught, the instinctive pull toward her swings the wringer frame, thus disengaging the gear. As soon as this disengaging movement is started, and the rocker starts to tilt, the thrust of the gears assists in the disengaging movement. Should the operator in the panic, instead of pulling, resist the forward movement of the frame by the free hand grasping the upper part of the frame, the free hand will engage the trip bar and release the pressure.

In order to yieldingly hold the wringer in its neutral position, the following mechanism is provided. The posts 34a are provided with cross-grooves 41 with inclined or cammed faces on the upper and lower walls of the grooves. The rockers are provided with ribs 42 which are adapted to enter these grooves. Nuts 43 are arranged at the outer ends of the studs 36 and springs 44 are tensioned between the nuts and the posts, thus drawing the ribs yieldingly into the grooves. The studs 37 move with relation to the stiles and permit of the movement of the rockers carrying the ribs into and out of the grooves. Thus the wringer frame is yieldingly held in neutral but can be forced to set or driving position either by a forward or backward movement, throwing the gear 33 into mesh with the gear 29 or 31 desired, these gears reversing the movement of the rolls. The rockers are wide enough so that they engage the arm 34 to limit the rocking movement, and consequently the rocking movement of the wringer.

When the wringer is in set position, the axes of the studs 37 and 36 are in the line AA and this line parallels with the direction of thrust of the gear 33 on line CD. This paralleling of the alignment is affected with either setting of the gear 33. Thus the thrust of the gear is neutralized by the setting of the link and does not lift the frame so as to disengage the gear, but as soon as the frame is moved slightly and the rocker swung from the line AA, the thrust of the gear assists in lifting the wringer on the rocker to neutral position. It will be noted that trip bars are arranged at both sides of the wringer and that a thrust upon the trip bar releases the pressure so that with a single thrust, the roll may be stopped and the pressure relieved.

What I claim as new is:

1. In a wringer or the like having a frame; rolls comprising shafts mounted in the frame; and a supporting head comprising a supporting arm; the combination with said head and frame of a swinging vertically movable connection between the head and the frame; a frame supporting connection between the arm and frame permitting a forward and back substantially equal movement at both ends of the bottom of the frame, comprising devices lifting the frame through such movement to a neutral position intermediate the ends of such movement; a safety device actuated with such lifting movement; and a device yieldingly holding the frame in neutral intermediate position.

2. In a wringer or the like having a frame; rolls comprising shafts mounted in the frame; and a supporting head comprising a supporting arm; the combination with said head and frame of a swinging vertically movable connection between the head and the frame; a frame supporting connection between the arm and frame permitting a forward and back substantially equal movement of both ends of the bottom of the frame, comprising devices lifting the frame through such movement to a neutral position in-

termidate the ends of such movement; and a safety device actuated with such lifting movement comprising a driven gear on one of the roll shafts; oppositely rotating driving gears on the head into and out of mesh with which the gear on the roll shaft may be swung by the movement of the frame; and devices yieldingly holding the frame in intermediate position.

3. In a wringer or the like having a frame; rolls comprising shafts mounted in the frame; and a supporting head comprising a supporting arm; the combination with said frame and supporting arm of a swinging vertically movable connection between the head and the frame; a frame supporting connection between the arm and frame permitting a forward and back substantially equal movement of both ends of the bottom of the frame, comprising devices lifting the frame through such movement to a neutral position intermediate the ends of such movement; and a safety device actuated with such lifting movement comprising a driven gear on one of the roll shafts, and oppositely rotating driving gears on the head into and out of mesh with which the gear on the roll shaft may be swung by the movement of the frame, the thrust of the driving gears being in a direction assisting in the disengagement of the driven gear when the wringer is moved to neutral.

4. In a wringer or the like having a frame; rolls comprising shafts mounted in the frame; and a supporting head comprising a supporting arm; the combination with said frame and arm of rockers pivotally mounted on the arm and spaced apart along the arm; pivotal connections between the rockers and the frame; a swinging and vertically movable connection between the frame and head vertically spaced from the rocker connections; and a safety device actuated with a lifting of the frame by the rockers as the frame is moved either in a forward or backward direction on the rockers depending on the direction of rotation of the rolls.

5. In a wringer or the like, the combination of a frame; rolls comprising shafts mounted in the frame; a supporting head comprising a supporting arm; rockers pivotally mounted on the arm; pivotal connections between the rockers and the frame; a swinging and vertically movable connection between the frame and head vertically spaced from the rocker connections; a gearing comprising oppositely rotating adjacent driving gears; and a gear on one of the said shafts swinging with the shaft and frame into and out of mesh with the driving gears and into neutral between them.

6. In a wringer or the like, the combination of a frame; rolls comprising shafts mounted in the frame; a supporting head comprising a supporting arm; rockers pivotally mounted on the arm; pivotal connections between the rockers and the frame; a swinging and vertically movable connection between the frame and head vertically spaced from the rocker connections; a gearing comprising oppositely rotating adjacent driving gears; a gear on one of said shafts swinging with the shaft and frame into and out of mesh with the driving gears and into neutral between them; and devices yieldingly holding the wringer in neutral position.

7. In a wringer or the like, the combination of a frame; rolls comprising shafts mounted in the frame; a supporting head comprising a supporting arm; rockers pivotally mounted on the arm; pivotal connections between the rockers and the

frame; a swinging and vertically movable connection between the frame and head vertically spaced from the rocker connections; a gearing comprising oppositely rotating adjacent driving gears; and a gear on one of said shafts swinging with the shaft and frame into and out of mesh with the driving gears and into neutral between them, the thrust of the driving gears being in approximately the same direction as lines connecting the axes of the pivots of the rockers.

8. In a wringer or the like having a frame, shafts and coacting pressure rolls mounted in the frame, a supporting head, and driving means for the rolls and a safety device, the combination with the head and safety device of a frame supporting connection between the head and frame permitting a forward and back movement of the lower portion of the frame and rolls and compelling with such movement a lifting of the frame to a neutral position intermediate the ends of such 20

movement, and devices responsive to such lifting of the frame making effective the safety device.

9. In a wringer or the like having a frame, shafts and rolls mounted in the frame, a supporting head comprising a supporting arm, and driving means for the rolls, the combination with said frame and supporting arm of a frame supporting connection between the arm and frame permitting a forward and back movement of the lower portion of the frame and compelling through such movement a lifting of the frame to a neutral position intermediate the ends of such movement, and a safety device made effective through such lifting movement comprising a driven gear on the shaft and oppositely rotative driving gears on the head into mesh with which the gear on the roll shaft may be swung by the movement of the frame.

WALTER L. KAUFFMAN, II.
